UNITED STATES PATENT OFFICE.

JOHN G. RUSSELL, OF FARMINGTON, MISSOURI.

FENCE-CLAMP.

1,069,727.

Specification of Letters Patent. Patented Aug. 12, 1913.

Application filed February 13, 1912. Serial No. 677,343.

To all whom it may concern:

Be it known that I, JOHN G. RUSSELL, a citizen of the United States, residing at Farmington, in the county of St. Francois 5 and State of Missouri, have invented a new and useful Fence-Clamp, of which the following is a specification.

This invention relates to fence clamps, and has for its object to provide an improved device of this character adapted to clamp or grip the strands of a woven wire fence, or the like, and which is adapted to be connected to a draft mechanism or stretcher for drawing the fence taut.

15 A further object of the present invention is to provide a device of this character which is simple, efficient and serviceable.

To the above ends, this invention is embodied in the novel construction and combination of parts elicited in the following description and pointed out in the appended claims, it being understood that this device is susceptible of alterations or deviations in its details within the scope of the appended 25 claims without departing from the spirit of the invention.

The preferred embodiment of the invention is illustrated in the accompanying drawings, wherein similar reference characters indicate similar parts, and wherein—

30 Figure 1 is a perspective view of the clamp as in use. Fig. 2 is a side elevation thereof, parts being broken away. Fig. 3 is a section on the line 3—3 of Fig. 2, being on an enlarged scale. Fig. 4 is a sectional view taken on the line 4—4 of Fig. 2. Figs. 5 and 6 are perspective views of details.

35 Referring in detail to the drawings, the numerals 10 and 11 designate two clamping bars or clamping members, which have their adjoining faces scarfed longitudinally and their respective outer faces 23 and 24 converging forwardly, or toward the front edges of the bars. The adjoining faces of the bars 10 and 11 have the respective rearward complementary seats 17 and 18, which have a gentle bevel, and the respective forward complementary seats 19 and 20 which 40 have a greater bevel, arranged at an obtuse angle relative to the respective seats 17 and 18, whereby the adjoining faces of the bars are scarfed longitudinally. The bars 10 and 11 are of wood or other suitable material, and the respective strips of metal, or 45 other similar material designated by the nu-

50 merals 21 and 22, are secured to the adjoining faces of the bars 10 and 11 at the inner edges of the seats 19 and 18. Plates 26 are arranged at the ends of the bars 10 and 11 and have U-shaped flanges 27 receiving the ends of the bars, the said flanges passing around the sides and front edges of the bars. A bolt 28, or other pivotal member, is passed through the ends of each of the flanges 27, and through the ends of the bars 10 and 11 adjacent their rear edges. A pair, or more if desired, of U-shaped clamping members 14 having diverging arms fit over the front edges and the sides of the bars 10 and 11 and each have a strengthening or reinforcing rib 15 extending around the outer sides thereof. The clamping members 14 are secured to the bar or member 10 by means of screws 16, or in any other suitable manner, and the bar 11 is split diagonally, as designated by the numeral 25, between the said clamping members 14, thereby dividing the bar 11 into the sections 12 and 13, the inner end of the section 12 overlapping the inner end of the section 13. The bolts or pivotal members 28 pivot the outer ends of the sections 12 and 13 of the bar 11 to the respective ends of the bar 10, thereby permitting the said sections to open and swing away from the bar 10 in "jack-knife" fashion, whereby the strands of the woven wire fence, or the like, may be received between the two bars. When the strands of a fence are brought 55 against the inner face of the bar 10, the sections 12 and 13 are swung against or folded against the bar 10, the scarfed faces of the two bars coinciding and the sections 12 and 13 of the bar 11 being received by the respective arms of the clamping members 14. The arms of the clamping members 14 diverging rearwardly and the outer faces of the sections 12 and 13 converging forwardly toward the outer face of the bar 10 cause the sections 12 and 13 to be pressed 60 against the bar 10 upon the sections being received by the clamping members 14, and in this manner the strands are securely clamped or gripped between the inner or adjoining faces of the clamping bars or clamping members 10 and 11, the strips 21 and 22 also binding the strands to assist in the clamping or gripping action.

65 In use, in applying the clamp to the strands of a fence, the clamp is arranged in an upright position adjacent the strands to

be clamped and the sections 12 and 13 of the bar 11 are then swung open rearwardly, whereby the strands may be brought against the inner or scarfed face of the bar 10. The 5 sections 12 and 13 are then brought on the other side of the strands, as the bar 10 is brought against the strands, and by swinging the said sections against the bar 10 the strands are securely clamped or gripped 10 between the inner or scarfed faces of the two bars, the clamping members 14 receiving the sections 12 and 13 and pressing the same tightly against the bar 10 to assist in the gripping or clamping action. The 15 sections 12 and 13 are pivoted to the bar 10 to swing rearwardly, and the clamp may therefore be applied to the strands of a fence in a comparatively small space, there being no laterally projecting or laterally 20 swinging members embodied in the clamp. This clamp is connected to a draft mechanism or stretcher by means of a clevis 29, or the like, which is engaged over the rear edges of the bars, whereby as the clamp is 25 drawn by the stretching mechanism or draft mechanism, the sections 12 and 13 are drawn into the clamping members 14 to bind the strands. By removing the clevis 29, the sections 12 and 13 may be readily 30 opened to release the strands of the fence, after the fence has been drawn taut and secured in position. In this manner, it will be noted that the clamp may be readily and conveniently attached to the strands of a 35 woven wire fence, or the like, in order that the fence may be stretched, and it will be noted that this device is simple in its construction, as well as efficient and serviceable.

Having described the invention, what is 40 claimed as new is:—

1. A fence clamp embodying two clamping bars, one bar being split intermediate its ends to form sections which are pivoted to the ends of the other bar and which are 45 adapted to open and swing away from the other bar for receiving the strands of a fence, and means for pressing the said sections against the other bar when the sections are folded against the said bar.

50 2. A fence clamp embodying two clamping bars, one bar being split intermediate its ends to form sections which are pivoted to the ends of the other bar and which are adapted to open and swing away from the 55 other bar for receiving the strands of a fence, and means carried by the latter bar to receive and press the said sections against the latter bar when the sections are folded against the said bar.

60 3. A clamp embodying two pivoted mem-

bers, and a U-shaped member straddling them to normally press them together and having one arm secured to one member, the other member being free to swing open.

4. A fence clamp embodying two clamping bars having their adjoining faces scarfed longitudinally and their outer faces converging forwardly, plates arranged at the ends of the said bars and having U-shaped flanges receiving the ends of the bars, pivotal members passing through the ends of the flanges and the ends of the bars, and U-shaped clamping members having diverging arms and fitting over the front edges and sides of the bars, said clamping members being secured to one of the bars and the other bar being split between the said clamping members to form two sections adapted to open and swing away from the former bar for receiving the strands of a 80 fence, and the said clamping members being adapted to receive the said sections when they are folded against the former bar and tending to press the sections against the said bar.

5. A fence clamp embodying two clamping bars, and U-shaped clamping members fitting over one of the edges and the sides of the bars, said clamping members being secured to one of the bars, the other bar being split between the clamping members to form two sections which are pivoted to the ends of the former bar and which are adapted to open and swing away from the former bar for receiving the strands of a fence, 95 said clamping members being adapted to receive the said sections when the sections are folded against the former bar.

6. A fence clamp embodying a clamping bar, a member pivoted thereto and adapted 100 to open in "jack-knife" fashion to receive the strands of a fence, and a member carried by the said bar to receive and press the said member against the bar when the member is swung against same.

105 7. A clamp embodying two pivoted members, having their outer faces converging forwardly, and a U-shaped member having diverging arms straddling the forward edges of the said members, and secured to one member, in order that the other member is pressed against the former member when received by the U-shaped member.

In testimony that I claim the foregoing as my own, I have hereto affixed my signature in the presence of two witnesses.

JOHN G. RUSSELL.
